ALARM SIGNAL

Filed Jan. 11, 1924

INVENTOR.
Alexander N. Pierman,
BY
Wm. H. Campfield.
ATTORNEY.

UNITED STATES PATENT OFFICE.

ALEXANDER N. PIERMAN, OF NEWARK, NEW JERSEY.

ALARM SIGNAL.

Application filed January 11, 1924. Serial No. 685,543.

This invention relates to an improved alarm signal which is adapted to be used primarily on automobiles and the like and is adapted to produce articulate sound in that 5 warning words or phrases can be emitted from the signal, these if desired, being in the form of the name of the car to which the signal is attached thereby also functioning as an advertisement.

10 The invention has for its object to provide a horn of this type which is simple in operation and which will clearly enunciate or articulate, thus simulating the human voice.

The invention is designed to provide a 15 horn which emits sound of material volume when the vibrating means moves in one direction and is practically silent when the vibrating means moves in the reverse direction. The horn thus requires but little power 20 to vibrate it and the ready return of the vibrating means permits a quick succession of sounds.

The invention also resides in certain 25 details of construction which will be herein- after more fully described and finally embodied in the claim.

Figure 1 is a section of a signal embodying my invention, the horn being shown at elevation. Figure 2 is a face view of the vibrating bar shown in Figure 1. Figure 3 is 30 a section similar to Figure 1 but illustrating a modified form of operating means and Figure 4 is a perspective view of an actuating bar shown in Figure 3. Figure 5 is a detailed section showing the stylus on an enlarged scale.

In Figure 1 I show a structure by means 35 of which a reciprocating bar acts directly on the stylus to cause the diaphragm to vibrate when the bar is moved in one direction and to produce no material vibration on the return stroke of the bar.

In the drawing I show the bar or rod 45

and the hand piece 47 by means of which it is operated in one direction, the return being accomplished by a spring 48, the bar being mounted in the suitable frame 49, the bar having the projecting part 50 into which the sound groove 51 is cut which sound groove is adapted to engage the stylus 52 45 which stylus is pivoted at 53 to the diaphragm between the plates 54 and has the finger 55 which abuts against the diaphragm or the fixed part of the stylus. When the rod 45 is pushed down, the diaphragm is vibrated but on the return stroke, the stylus 50 swings on the pivot 53 and in this tilted position, causes no material vibration of the diaphragm.

In Figure 3 I show a still further modified 60 form in which the diaphragm is provided with a similar tilting stylus 52 but the actuating bar or rod 56 is provided with an extension 57 and has a slot 58 in which the pin 59 of the gear 60 slides, the gear 60 being in mesh with a pinion 61 on the motor 62.

This type of horn can be operated by a 65 push button as is the usual electrical horn. The open space 63 underneath the raised portion 50 provides for sufficient play so 70 that the rod has acquired speed in its movement before the stylus is engaged.

I claim:

An alarm signal comprising a vibratile 75 diaphragm, a stylus secured to the dia- phragm so as to tilt thereon, a support, and a bar in the support and adapted to recipro- cate and having a surface to force the stylus to vibrate the diaphragm when moved in one direction, the stylus tilting and being with- 80 out function on the return stroke of the bar and means for reciprocating the bar.

In testimony that I claim the foregoing, I have hereto set my hand, this 20th day of December, 1923.

A. N. PIERMAN.
